UNITED STATES PATENT OFFICE.

WILLIAM F. RUNNELLS, OF NEWBURYPORT, MASSACHUSETTS.

DIAPHRAGM-PUMP.

SPECIFICATION forming part of Letters Patent No. 696,696, dated April 1, 1902.

Application filed September 20, 1901. Serial No. 75,818. (No model.)

To all whom it may concern:

Be it known that I, WILLIAM F. RUNNELLS, of Newburyport, in the county of Essex and State of Massachusetts, have invented certain 5 new and useful Improvements in Diaphragm-Pumps, of which the following is a specification.

This invention relates to diaphragm-pumps; and its objects are to increase the strength 10 and rigidity of such structures and to simplify the same.

The means in which my invention consists whereby such objects are attained I shall now proceed to set forth and claim.

15 Of the accompanying drawings, Figure 1 represents a vertical section of a diaphragm-pump constructed in accordance with my invention. Fig. 2 represents a detail side elevation of the inlet-valve. Fig. 3 represents 20 a similar detail of the plunger-beam. Fig. 4 represents a similar detail of the brake or operating-lever. Fig. 5 represents a similar detail of the outlet-valve. Fig. 6 represents a 25 section of the plunger-beam on the line Z Z' of Fig. 3.

The same reference characters denote the same parts in all the figures.

The casing of the pump is made up of upper and lower parts I I', detachably secured 30 together by bolts K K', passing through lugs L L', and the flexible diaphragm E has its edges confined between said upper and lower parts. Below the diaphragm is the suction-chamber S, having an inlet-aperture formed 35 in a cylindrical flange V, which aperture is controlled by the inlet-valve D, having the packing-washer H.

Above and below the diaphragm E, respectively, are located plates or disks O and M, 40 forming the body of the vertically-movable plunger and confining between them the diaphragm E, through which and the said upper and lower plates extends an outlet-aperture. The said aperture is controlled by a vertically-movable outlet-valve F, formed with 45 suitable downwardly-projecting guiding-lugs and having a packing-washer G, normally resting on the valve-seat formed around the upper edge of the outlet-aperture.

50 The two plates O M are detachably secured together by bolts N N', passing through the

two hollow uprights P P', which project upwardly from the upper plate O on opposite sides of the outlet aperture. At their upper ends these uprights are connected by the 55 transverse plunger-beam or cross-head A, secured in place by the bolts N N'. It will be noted that said plunger-beam is integrally formed with downwardly-projecting lugs T T', extending a considerable distance down 60 each of the uprights P P' and formed to closely fit or conform to the inner side surfaces of said uprights. These lugs make extended bearings between the plunger-beam A and the uprights P P', which add to the 65 strength, rigidity, and permanency of the plunger structure, while they also extend, as will be noted in Fig. 1, into sufficient proximity to the outlet-valve F to form stops for the latter, which the valve may encounter in 70 its upward or opening movement, whereby said movement is limited, the location of the lower ends of the lugs being such that the guide-lugs of the valve are prevented from entirely leaving the outlet-aperture. The 75 valve and plunger structure thus provided is superior in the qualities stated above of strength, rigidity, and permanency to prior pumps of this character and also in simplicity, certainty of operation, and cheapness 80 of manufacture.

B represents the operating-lever or brake pivoted upon a pin supported by suitable lugs on the rim of the upper part I of the pump-casing. The inner end of said lever 85 engages the pivot or bearing member of the plunger-beam A, the engaging parts being of the form particularly shown in Figs. 4 and 6, their bearing-surfaces being chilled to reduce wear. The lever B is formed with a lower 90 bearing-lip B', projecting from its body portion, and an upper overhanging bearing-lip or guard-lip B'', projecting from said body portion.

I claim—

95 In a diaphragm-pump, the combination of the diaphragm and plunger, said structure formed with an outlet from the pump-chamber, the plunger including a plate attached to the diaphragm and provided with a plurality of uprights on opposite sides of the outlet, a detachable cross head or beam con-

neected to the upper ends of said uprights and integrally formed with a plurality of downwardly-projecting lugs conforming to the uprights and constituting elongated bearings between said uprights and the cross-head, said lugs being also arranged to act as upper stops for the outlet-valve, and an outlet-valve supported by the diaphragm and plunger structure and controlling said outlet, the

said valve being adapted to encounter said lugs in its upward movement.

In testimony whereof I have affixed my signature in presence of two witnesses.

WILLIAM F. RUNNELLS.
